ELECTRIC CIRCUIT BREAKER

Herbert E. Brannon, Detroit, Mich.

Application February 15, 1940, Serial No. 319,009

3 Claims. (Cl. 200—113)

This invention relates to automatic electric circuit breakers of the type employing laminated temperature responsive elements as the means for breaking the circuits in which they are incorporated.

The principal object of the invention is to provide a circuit breaker of the type mentioned above which is more accurate and efficient than those previously known by reason of the fact that two independently actuated laminated elements are employed. Another object of the invention is to provide a circuit breaker having means for compensating for variations in ambient temperatures. Another object is to provide a circuit breaker having a means for breaking the circuit quickly upon the attainment of a predetermined temperature of said means.

These objects will more fully appear in the following specification, reference being had to the accompanying drawing, wherein:

Figure 1 is a cross-sectional view of a device embodying the invention;

Figure 2 is an exploded cross-sectional view of the device shown in Figure 1;

Figure 3 is a cross-sectional view taken on substantially the line 3—3 of Figure 1;

Figure 4 is a plan view of one of the laminated elements incorporated in the invention;

Figure 5 is a plan view of a fusible metal link used in the invention;

Figure 6 is a cross-sectional view of a slightly modified form of the invention; and

Figure 7 is a cross-sectional view of a still further modified form of the invention.

Figures 1 to 5 of the drawing illustrate a circuit breaker having an outer shell 10 which consists of a body portion 11 and a base 12. The two parts of the shell are preferably molded from suitable insulating material, such as porcelain or a synthetic resin. The body 11 is hollow, as shown in Figures 1 and 2 and is substantially cylindrical in cross-section. The side wall of the body is provided with molded threads 13 for a purpose which will presently appear. At one side of the body is a notch 14. The inner wall of the body 11 adjacent its open end is provided with an annular rabbet 15.

The base 12 is circular in plan and of the cross-section shown in Figures 1 and 2. Its diameter is the same as the diameter of the open end of the body 11. In the center of the base is an aperture 16.

The base 12 is mounted with its rim flat against the open end of the body 11. It is retained in place by means of a retaining ring 17. The side

wall of the retaining ring is corrugated to form helical threads 18, and has a radial flange 19 at one end. The threads 18 cooperate with the threads 13 on the body 11 and the flange 19 fits over the outer rim of the base 12 to hold the parts together.

Mounted within the rabbet 15 between the body 11 and the base 12 is a metal ring 25 to which a fusible link 20 is connected, a laminated resistor 21, an insulating ring 22, a second laminated resistor 23, and a substantially frustoconical terminal element 24, in the order named.

One end of the fusible link 20 is connected to the ring 25. Preferably the link 20 and ring 25 are stamped from one piece of sheet zinc or other suitable metal of low melting point. The ring 25 has formed in it a plurality of radially extending axially offset grooves 25a, the purpose of which will appear presently. The fusible link 20 has a pair of narrow necks 28. The cross-section of the necks is such that the resistance thereof creates sufficient heat to melt them if the current flowing therein exceeds a predetermined amount. The free end 27 of the fusible link 20 is bent to lie alongside of the body 11.

The laminated metal resistors 21 and 23 are both identical. Each resistor is of cruciform shape having 4 arms 29 radiating from its center, as shown in Figure 4, and is made up of thin sheets of two dissimilar metals 30 and 31 having their adjacent faces intimately secured together. Secured to the center of resistor 21 is a contact 32 of silver, or other suitable material. A similar contact 33 is attached to the center of resistor 23. The metal sheet 31 in each resistor has a low coefficient of expansion, and the sheet 30 has a high coefficient of expansion. It will be noted in Figure 2 particularly that the resistors are mounted with the high expansion sides 30 remote from each other and the low expansion sides 31 adjacent each other.

The insulating ring 22 is simply a cylinder of short axial length formed from any suitable insulating material, such as porcelain or synthetic resin.

The terminal 24 is for the most part frustoconical in shape, but is provided at its upper edge with a radial flange 35 and at its lower end with a cylindrical tip 34. The tip 34 is adapted to fit within the aperture 16 in the base 12 and project slightly from the outer surface of said base. The flange 35 has a plurality of downwardly offset radial grooves 36 therein.

The assembly of the various elements previously described is believed to be obvious from an in-

spection of Figures 1 and 2. The various elements are inserted into the body 11 in the order shown in Figure 2. The free ends of the arms 29 of the resistors 21 and 23 lie in the grooves 25a and 36 in the ring 25 and terminal element 24 respectively. The arms 29 are loose in their respective grooves to permit the ends of the arms 29 to move slightly in their own planes. The free end 27 of the fusible link extends through the notch 14 and overlies the outer surface of the body 11. The retaining ring 17 holds all of the parts together and touches the free end 27 of the fusible link 20, thereby forming one terminal of the circuit breaker. The other terminal is element 24.

The device just described is primarily adapted for use in a standard fuse plug socket, such as is ordinarily found in household wiring systems. When current is flowing in the line it passes from the cylindrical tip 34 of the terminal element 24 out to its rim 35, thence through the arms 29 of the resistor 23 to the contact 33, then to the contact 32 on the resistor 21, and out through the arms 29 of said resistor 21 into the metallic ring 25. From this point the current flows through the fusible link to the retaining ring 17 which forms the other terminal of the device.

The two laminated resistors 21 and 33 have a predetermined resistance to the flow of current through the circuit breaker. Current passing through the resistors causes them to heat up and deflect away from each other because they are so mounted as to deflect in opposite directions. As soon as there is any appreciable movement of the two parts the contacts 32 and 33 move apart, and the circuit is broken.

Since there are two of the laminated resistors, the amount of movement for any given temperature rise will be more than if only one of these elements is used. Accordingly, the circuit will be broken more sharply than it would be if only one were employed, and there will be much less arcing between the contacts.

If the circuit becomes heavily overloaded by reason of a short circuit in the line, the fusible link 20 will melt at either one or both of the necks 28 before the resistors 21 and 23 can reach the predetermined temperature at which they separate, and the circuit will be permanently broken. Thus it will be seen that the device provides a circuit breaker which automatically takes care of small and more or less temporary overloads which occasionally occur in the wiring system without necessitating the replacement of a fuse, yet in the event that the circuit is heavily overloaded the fusible link melts and the circuit is not endangered.

The structure shown in Figure 6 is similar to that previously described, but differs primarily in that but one of the two laminated temperature responsive elements is in the circuit and is consequently a resistor. The other laminated temperature responsive element is responsive to ambient temperature only.

The device comprises a shell 50 having a body 51 and a base 52, the former having threads 53 thereon. The body 51 has a notch 54 in one side wall and an internal rabbet 55 in its open end. Surrounding the body side wall is a retaining ring 56 which holds the base 52 to the body 51.

Mounted in the rabbet 55 is a metal ring 57, a laminated temperature responsive element 58, an insulating ring 59, a second temperature responsive element 60, in this case a resistor, and a terminal element 61 in the order named.

The metal ring 57 is a sheet metal ring having offset grooves therein similar to the grooves 25a in the ring 25.

The temperature responsive element 58 is of cruciform shape and made up of two dissimilar metal sheets 62 and 63. Metal sheet 62 is the high expansion side and sheet 63 is the low expansion side of the element. At its center is a contact 64 which is connected directly to one end of a fusible link 65. The other end 66 of the fusible link passes out through notch 54 and touches the retaining ring 56, thereby making the latter one terminal of the circuit breaker.

The temperature responsive element 60, hereinafter called a resistor, is also of cruciform shape and has a contact 67 at its center, normally engaging contact 64. The resistor 60 is made up of three laminated metal sheets 68, 69 and 70. Resistor 60 is designed to have the same expansion characteristics under ambient temperature as element 58. Therefore the coefficients of expansion of metallic sheets 68 and 70 of resistor 60 are the same as sheets 62 and 63 respectively of element 58. Sheet 69 of resistor 60 has the same coefficient of expansion as either sheet 68 or sheet 70, but has a higher resistance. If sheet 69 has the same coefficient of expansion as sheet 68, the combined cross sectional area of the two at any point must be the same as the corresponding cross section of sheet 62 in element 58, and the cross sectional area of sheet 70 must correspond with that of sheet 63. On the other hand, if sheet 69 has the same coefficient of expansion as sheet 70, then the combined cross section of sheets 69 and 70 must equal that of sheet 63, while the cross section of sheet 68 must be the same as sheet 62.

Thus, the high expansion and low expansion sides respectively of the element 58 and resistor 60 are the same in cross-section and have the same expansion characteristics for a given ambient temperature change. However, in resistor 60 either the high or the low expansion side is composed of two sheets of metal having the same coefficient of expansion and different resistances.

The terminal element 61 is identical to the terminal element 24 previously described and has a tip 71 projecting through an aperture in the base 52.

In the structure just described the path of the current is through the terminal element 61, then through resistor 60 to contact 67. From this contact 67 it passes to contact 64 and directly into the fusible link 65 from which it passes to retaining ring 56, the other terminal of the device.

Thus it will be seen that temperature responsive element 58 is not in the circuit. Its sole purpose is to compensate for variations in the ambient temperature of the laminated temperature responsive elements. It deflects in the same direction as resistor 60 under a corresponding temperature change.

The presence of the high resistance center metal sheet 69 in the resistor 60, causes it to attain a high temperature in a relatively short time when current flows through it. This results in a greater deflection of the entire resistor 60 than would be obtained with a similar resistor of bimetal. When current passes through it, the resistor 60 attains a much higher temperature than element 58. Therefore, even though element 58 deflects slightly under an increase in the ambient temperature, resistor 60 deflects more and will break the circuit when the current passing through it reaches a predetermined quantity.

Figure 7 shows another modified form of the invention. It comprises a shell 100 consisting of a body 101 and a base 102. The body 101 has an annular groove 103 at its open end.

Located within the groove 103 is a fusible link 104, identical with link 20, and having one end connected to a ring 105. Next to the ring is a laminated resistor 106, then an insulating ring 107, another laminated resistor 108, and finally a terminal element 109 having a cylindrical tip 110 projecting through an aperture in the base 102. A retaining ring 111 is mounted over the shell in the same manner as the ring 17 in Figures 1 and 2 and held in place by threads 112 on the body 101.

The resistors 106 and 108 are of cruciform shape, the same as resistor 29 in Figure 4, and are provided with contacts 113 and 114 respectively at their centers. Resistor 106 is made up of two dissimilar metals 115 and 116, and resistor 108 consists of two dissimilar metals 117 and 118.

The two resistors are made of metals such that the coefficient of expansion of each resistor is the same, but their internal resistances are different, that of resistor 106 being greater than resistor 108. Furthermore, the resistors are mounted so that the low expansion side of resistor 106 is adjacent the high expansion side of resistor 108. In other words, metals 116 and 118 have lower coefficients of expansion than metals 115 and 117 respectively.

When the circuit breaker is connected into an electric circuit, the path of the current is the same as that in the device shown in Figures 1 and 2. It flows from the tip 110 through the entire terminal element 109, and then through the arms of resistor 108 to the contact 114. From contact 114 it flows to contact 113, through the arms of resistor 106 to the ring 105, and finally through link 104 to the retaining ring 111, the latter being the other terminal of the circuit breaker.

Thus it will be seen that when a current passes through the device both resistors are heated because of their resistance to the flow of current, and both resistors deflect in the same direction. Because resistor 106 has a higher resistance than resistor 108, the former attains a higher temperature and consequently deflects more than the other resistor, thereby breaking the circuit. However, since the coefficients of expansion are the same, any change in ambient temperature within the shell will cause a corresponding deflection in both resistors, thereby compensating for variations in ambient temperature.

In all three of the modifications disclosed the laminated temperature responsive elements are designated as of "cruciform" shape, and element 21 is shown as having four arms. This particular shape, however, is not essential, and there may be more or less than four arms. In each case, however, the laminated element must be supported at the extremities of its arms, and the contact must be mounted remote from the extremities, preferably at the center. Furthermore, the arms must be supported on the shell loosely enough to permit a slight movement of the ends of said arms in their own plane, to permit the element to deflect.

From the foregoing it will be apparent that the basic feature of the invention is in the provision of two laminated temperature responsive elements acting independently of each other. This results in a quick acting circuit breaker in which provision is made for counteracting the effect of ambient temperatures and thereby providing a very accurately controlled device.

The scope of the invention is indicated in the appended claims.

I claim:

1. A circuit breaker comprising an insulating support, two spaced terminals on said support, a pair of laminated temperature responsive elements mounted on said support, one of said elements being an electrical resistor composed of three layers of metal, two of said layers having the same coefficient of expansion and one of said last mentioned layers having a greater resistance than the other, each of said elements having a contact thereon normally touching each other and adapted to separate upon a predetermined increase in the temperature of said resistor element, a connection between one of said terminals and said resistor element at a point remote from the contact thereon and a connection between the other element and the other terminal.

2. A circuit breaker comprising a shell, two spaced terminals supported by a wall of said shell, a pair of laminated temperature responsive resistors each comprising a central portion and a plurality of arms radiating therefrom, said resistors being mounted within the shell and supported thereon solely by the extremities of the arms for limited movement of the latter in the planes of the resistors, said resistors being adapted to deflect in the same direction upon a corresponding change in the temperatures thereof, said resistors having contacts thereon adjacent their centers normally touching each other, a connection between one of said terminals and one of said resistors at a point remote from the contact thereon, and a connection between the other terminal and the other resistor at a point remote from its contact, one of said resistors being adapted to deflect more than the other upon a predetermined change in the current flowing through them.

3. A circuit breaker comprising a shell, two spaced terminals supported by a wall of said shell, a pair of laminated temperature responsive elements each comprising a central portion and a plurality of arms radiating therefrom, said elements being mounted within said shell and supported thereon solely by the extremities of the arms for limited movement of the latter in the planes of the elements, one of said elements being an electrical resistor composed of three layers of metal, two of said layers having the same coefficient of expansion and one of said last mentioned layers having a greater resistance than the other, each of said elements having a contact thereon normally touching each other and adapted to separate upon a predetermined increase in the temperature of said resistor element, a connection between one of said terminals and said resistor element at a point remote from the contact thereon, and a connection between the other element and the other terminal.

HERBERT E. BRANNON.
